UNITED STATES PATENT OFFICE.

LOUIS BESSIÈRE, OF PARIS, FRANCE, ASSIGNOR TO PAUL DURAND, OF NEW YORK, N. Y.

DESIGN FOR A DRINKING VESSEL.

SPECIFICATION forming part of Design No. 36,124, dated October 28, 1902.

Application filed September 16, 1902. Serial No. 123,660. Term of patent 7 years.

To all whom it may concern:

Be it known that I, LOUIS BESSIÈRE, a citizen of the Republic of France, and a resident of the city of Paris, in the department of Seine, France, have invented and produced a certain new, original, and ornamental Design for a Drinking Vessel or Similar Article, of which the following is a specification.

My design is illustrated in the accompanying drawing, referred to herein, which shows a drinking vessel with the design thereon.

The piece A consists of three ornaments composed of curved lines connected by a small transverse bar at the center. The ornament B, consisting of a branch bearing leaves, extends from the bottom thereof. On either side of the ornament A are reversed spiral ornaments C, from the upper part of which proceeds a small branch D, bearing leaves. The ornamentation thus described

is repeated a number of times to form a continuous band or border extending around the vessel.

The body X of the vessel is otherwise plain and rounded at the bottom. It is supported by a slender stem X', terminating at the disk-shaped base X². The shape of the vessel, however, is not new, and it will be apparent that the ornamentation above described may be placed on differently-shaped vessels. 25 30

What I claim is—

The ornamental design for a drinking vessel or similar article substantially as herein shown and described.

Signed at the city of Paris, in the Department of Seine, this 31st day of July, 1902. 35

LOUIS BESSIÈRE.
